LOOM HARNESS

Filed Dec. 1, 1934

UNITED STATES PATENT OFFICE

2,010,786

LOOM HARNESS

John Jacob Kaufmann, Elkins Park, Pa., assignor to Steel Heddle Manufacturing Company, Philadelphia, Pa., a corporation of Pennsylvania

Application December 1, 1934, Serial No. 755,530

7 Claims. (Cl. 139—88)

This invention relates to improvements in loom harness, with particular reference to the connectors for the heddle frames of such harness. More specifically, the invention comprises an improved form of harness connector with novel features of construction, which may be used for heavy frames particularly.

The harness connectors heretofore most commonly used do not combine adequate strength with provision for ease of mounting and adjustment. It is an object of this invention, therefore, to overcome the difficulties heretofore encountered in these respects.

A further object of the invention is to provide a harness connector which is sturdy in construction and suitable for heavy frames, and which at the same time is not complicated in its details.

A further object of the invention is to provide a harness connector which may be easily applied to or removed from a harness frame, yet which will be securely attached to the frame when in use.

A further object of the invention is to provide a clamping structure for use with a harness connector, which will provide adequate bearing surfaces between pivotally mounted portions thereof.

Additional objects of the invention will be obvious from the specification and claims.

In the accompanying drawing, wherein is shown a preferred embodiment of the invention,

Figure 1 is a front elevation of a harness frame with the invention applied thereto;

Fig. 2 is a rear elevation, on a somewhat larger scale than Fig. 1, of the harness frame connector;

Fig. 3 is a front elevation similar to Fig. 2;

Fig. 4 is an end elevation, with the rail of the harness frame shown in vertical section on the line 4—4 of Fig. 1; and

Fig. 5 is a horizontal section through a portion of the connector, taken on the line 5—5 of Fig. 4.

It will, of course, be understood that the description and drawing herein contained are illustrative merely, and that various modifications and changes may be made in the structure disclosed without departing from the spirit of the invention.

Referring more particularly to the drawing, it will be seen that there is provided a harness frame of a usual type, having horizontal rails 10 connected by end members 11. Rods 12, which are mounted in the frame in any preferred manner, carry the heddles 13 thereon.

Connectors embodying the invention are shown on the upper and lower rails 10. While two

connectors have been shown at the top and at the bottom, respectively, additional connectors may be used if desired.

Each connector comprises a rail engaging member 14, which may embrace a rail on three sides, and is under an initial gripping tension when applied to the rail. This rail engaging member 14, which is preferably made from strap metal, is generally U-shaped when viewed from the end, and has flat walls 15 in conformity with the parallel front and rear faces of the rail 10. The walls 15 are joined by a portion 16, which may be shaped to conform to the inner edge surface of the top or bottom rail, as the case may be. The flat walls 15 have offset portions 17 integrally connected therewith, and these offset portions 17 merge with end portions 18 which are spaced apart, project beyond the rail, and are substantially parallel to the walls 15. The offset portions 17 may also contact and hold the rail as shown in Fig. 4. The end portions 18 have aligned holes therein for the reception of portions of the clamping structure as hereinafter pointed out.

A harness strap receiving member 19 is also provided. This member 19 may have an elongated part with an opening therein, as shown at 20, for the reception of a flat harness strap (not shown), or may have a toroidal part 21 with a circular aperture therethrough, as shown at 22. This aperture may take any preferred form, in accordance with the type of harness strap employed, or if desired a hook may be provided.

The strap receiving member 19 has a bearing collar 23, formed with parallel flat faces for reception between the end portions 18 of the rail engaging 14, and has an opening therethrough for alinement with the openings in the aforesaid end portions 18. The metal surrounding the opening serves as a bearing surface, as hereinafter pointed out.

Clamping structure, the details of which may be seen in Fig. 5, is provided for holding the rail engaging member 14 and the harness strap receiving member 19 in the desired assembled relationship. The clamping structure includes a horizontally disposed cylindrical bearing pin 24, preferably arranged perpendicular to the longitudinal axial plane of the harness frame.

The outer face of the bearing pin 24 is in engagement with the inner cylindrical wall of the opening in the collar 23. The bearing pin 24 is provided at one end with a head 25, which may be hexagonal in shape.

In order to prevent turning of the head 25,

and at the same time permit easy removal of the bearing pin 24, projections 26 may be punched or otherwise formed in the adjacent end portion of the rail engaging member 14.

5 The bearing pin 24 extends through the apertures in the end portions 18, and through the opening in the collar 23.

A machine bolt or screw 27, with a slotted head 28 which does not project beyond the harness 10 strap receiving member 21, has threads which engage the internally threaded portion of the bearing pin 24. This machine screw 27 serves to hold the cylindrical bearing pin 24 in position. A washer 29 is interposed between the head 28 15 of the machine screw 27 and the adjacent end portion 18.

The manner of attaching the connector to a harness frame, and the action thereof when in use, will now be described.

20 The rail engaging member 14 is applied to the rail 10 by springing the end portions 18 apart so that they may pass over the front and rear faces of the rail. This member 14 then engages the rail embracing and gripping the same by reason of 25 the initial gripping tension thereof as well as by reason of the offset portions 17 which tend to guide the member to its final position on the rail and maintain it there by their own confining action. No undue or undesired movement of the 30 member 14 with respect to the rail 10 will occur when the rail engaging member has been brought to its gripping position. The rail engaging member 14, even though made of one piece of metal, may be applied to a heddle frame having heddles 35 mounted therein with the same facility as to a frame without heddles.

The collar 23 is then placed between the end portions 18, with its opening in alinement with the apertures in said end portions, and the bearing pin 24 of the clamping structure is inserted. 40 The clamping structure may then be tightened by means of the machine screw 27, to secure the collar 23 under the desired degree of tightness. No difficulty will be encountered in tightening the 45 clamping structure, since the screw 27 may be of sufficient length to engage the internal threads of the bearing pin 24 before the clamping action occurs, and the head 25 will be restrained from rotation by the projections 26. The large bearing 50 surfaces provided between the collar 23 and the bearing pin 24 preclude any excessive strains being set up, and avoid any tendency to disturb the relative positions of the rail engaging member 14 and the harness strap receiving member 19.

55 It will be noted that the harness strap receiving member 19 tends to take a position properly in alinement in accordance with the position assumed by the harness strap.

I claim:

60 1. In a harness connector for looms, a member 65 gripping the rail of a heddle frame, a harness strap receiving member, and means for connecting said members in pivotal relationship, said means including a bearing pin internally threaded, and a bolt for preventing displacement of said bearing pin.

2. In a harness connector for looms, a member gripping the rail of a heddle frame, a harness strap receiving member, and means for connecting said members in pivotal relationship, said means including a bearing pin journaled in a portion of said strap receiving member and being internally threaded, and a bolt for preventing displacement of said bearing pin. 5

3. In a harness connector for looms, a member gripping the rail of a heddle frame, a harness 10 strap receiving member, and means for connecting said members in pivotal relationship, said means including a horizontally disposed bearing pin fixed against rotation with respect to said rail gripping member, said bearing pin being internally threaded, and a bolt for preventing horizontal 15 displacement of said bearing pin.

4. In a harness connector for looms, a U-shaped member gripping the rail of a heddle frame, end 20 portions projecting from said member beyond said rail, a harness strap receiving member provided with a portion for reception between said end portions, and clamping devices therefor comprising a pin having an internally threaded portion, and means engaging said internally 25 threaded portion for holding said pin in position.

5. In a harness connector for looms, a U-shaped member gripping the rail of a heddle frame, end 30 portions projecting from said member beyond said rail, a harness strap receiving member provided with a portion for reception between said end portions, and clamping devices therefor comprising a pin fixed against rotation with respect to said end portions, said pin having an internally threaded portion, and means engaging 35 said internally threaded portion for holding said pin in position.

6. In a harness connector for looms, a unitary member gripping a plurality of faces of the rail 40 of a heddle frame, said member having end portions projecting beyond said rail, a harness strap receiving member provided with a portion for reception between said end portions, and clamping devices therefor comprising a member fixed against rotation with respect to said end portions 45 and having an internally threaded portion, and a bolt engaging said internally threaded portion for holding said last named member in position.

7. In a harness connector for looms, a one piece 50 member gripping a plurality of faces of the rail of a heddle frame, said member having end portions, a strap receiving member having a portion for reception between said end portions, and clamping devices therefor comprising a pin member 55 extending through said end portions and a portion of said strap receiving member and fixed against rotation with respect to said end portions, said pin member having an internally threaded portion, and a bolt for engagement with said internally threaded portion, the head of said bolt being within the extremities of said strap receiving member. 60

JOHN JACOB KAUFMANN. 65
